J. Y. Elliott, Jr.

INVENTOR.

Charles B. Morehouse

UNITED STATES PATENT OFFICE.

CHARLES B. MOREHOUSE, OF NEWCASTLE, INDIANA.

WHIP-SOCKET.

Specification forming part of Letters Patent No. 43,858, dated August 16, 1864.

To all whom it may concern:

Be it known that I, CHARLES B. MOREHOUSE, of Newcastle, Henry county, Indiana, have invented a new and useful Improvement in Whip-Sockets; and I do hereby declare that the following is a full and exact description of the same, reference being had to the drawing therewith, and to the letters of reference thereon, forming a part of the same.

In the drawing, D represents the bar of the dash of the carriage or buggy, and A is the whip-socket for the reception of the whip.

B represents the clamps or arms resting at a a and terminating at b' b', by which the said arm, being secured by the screws and nuts c c.

embraces the bar of the dash without having the leather perforated.

The socket may be made of the ordinary form, and the clamp is readily accommodated to any of the forms in use.

What I claim as new, and desire to secure by Letters Patent, is—

As an article of manufacture, the clamps or arms B and b and the nuts C C, substantially as described, for the purpose of attaching a whip-socket to a dash without making a hole in the leather or dash.

Attest: CHARLES B. MOREHOUSE.

J. W. PITMAN,

M. M. VESTUL.
